TELEPHONE AMPLIFIER CABINET

Robert L. Gallup, Niles, Mich., assignor, by mesne assignments, to Daystrom, Incorporated, Murray Hill, N.J., a corporation of Texas

Filed Sept. 1, 1961, Ser. No. 66,629

Term of patent 14 years

(Cl. D26—14)

FIG. 1

FIG. 3

The telephone handset shown in broken lines in FIGURE 1 is for illustrative purposes only.

I claim:
The ornamental design for a telephone amplifier cabinet, substantially as shown and described.
